UNITED STATES PATENT OFFICE

106,265

DESIGN FOR A PRINTED FABRIC

Irving Sherman, New York, N. Y.

Application August 31, 1937, Serial No. 71,408

Term of patent 3½ years

To all whom it may concern:

Be it known that I, Irving Sherman, a citizen of the United States, residing at 1172 President Street, in the county of Kings, city and State of New York, have invented a new, original, and ornamental Design for a Printed Fabric, of which the following is a specification, reference being had to the accompanying drawing, constituting a part thereof:

The figure is a plan view of a piece of the fabric showing my new design.

I claim:

The ornamental design for a printed fabric substantially as shown.

IRVING SHERMAN.
